MACHINE FOR APPLYING TIRE PATCHES

Clarence E. Dunlap, Sioux City, Iowa

Application December 31, 1934, Serial No. 759,894

9 Claims. (Cl. 18—18)

My invention relates to an improved apparatus for applying either hot or cold patches to a tube.

An object of my invention is to provide a device of such character which can be readily accommodated for use with either cold or hot patches.

A further object of my invention is to provide a device of this character which will allow changing of the machine to apply either type of patch as desired.

10 A further object of my invention is to provide adjustable means so that either a minimum or a maximum pressure can be applied, at the same time rendering the apparatus fool proof so that undue pressures will not be set up when such are 15 not desired.

A further object of my invention is to provide a structure associated with the device so that heat can be readily applied to the patch, which heat is concentrated in a highly effective manner.

20 A further object of my invention is to provide means for centering a patch on the tube, and to further provide means for applying different size patches.

25 A further object of my invention is to provide a structure of extreme simplicity which will attain the result above mentioned, and which can be manufactured at a reasonable cost.

With these and other objects in view, my invention consists in the construction, arrangement 30 and combination of the various parts of my device, whereby the objects contemplated are attained, as hereinafter more fully set forth, pointed out in my claims, and illustrated in the accompanying drawing, in which:

Figure 1 is a side elevation of one form of the device,

Figure 2 is a plan view of the device,

Figure 3 is an enlarged sectional detail taken medially of the device,

Figure 4 is a preferred modified form of the device in sectional detail,

Figure 5 is an outside view of the modification disclosed in Figure 4, and

45 Figure 6 shows the device when used on a cold patch.

In applying a hot patch to a tube, in other words that type of patch which requires or uses heat, care must be taken that extreme pressures 50 are not applied against the patch, since such extreme pressures would tend to distort the patch out of shape and unduly affect the material of the patch.

On the other hand, a cold patch, or that type of 55 patch which does not require heat, must be applied

with a very great pressure to insure a firm bonding with the tube.

The principal object contemplated in the present invention is to provide means for easily and readily changing the device for use with hot or cold patches as desired without the necessity of removing or changing parts associated with the device.

I have used the character 10 to indicate the frame of this machine itself, which preferably is 10 made of a suitable grade of high strength cast iron or the like. The frame 10 includes the portion 11 which receives the plunger 12 which slides within the opening 13.

The plunger 12 includes the plunger head 14 15 beneath which is positioned the spring 15. The plunger head 14 includes the rounded portion 16 which is adapted to co-act with the cam portion 17 which pivots at pin 18 and extends into the integral lever 19.

In one form of the device, the lever 19 receives the further telescoping element 20 which includes the head 21. Figure 1 shows the elements telescoped together and also with the member 20 pulled out.

20 The plunger 12 is forced downwardly by virtue of the cam member 17 pressing against the portion 16, and it will be noted that an extremely large leverage is obtained by virtue of the difference in length between the lever 19 and the 30 relatively short member 17. It will be noted that when the members are telescoped together that a smaller pressure will be set up through the plunger 12 and a larger pressure will be set up when the telescoping member 20 is pulled outwardly 35 since the lever arm comprising the added lengths of the members 19 and 20 is much longer.

25 Formed together with the plunger 12 is the reduced diameter extension 22 into which is threadedly engaged at 23 the hardened member 40 53 which has the lower rounded surface 54 as shown.

The column 22 receives the four-armed spider frame 55 which is rounded at 56 and which bears against the shoulder 57 of the post 12.

45 The headed pins 58 are attached to the fuel cup or pan 24 which is normally of circular shape, and which cup includes the bottom 33 and the sides 34.

The spider 55 includes the opening 59 which is made larger than the post 22 to allow free pivoting movement of the spider against the shoulder 57.

The pins 58 are affixed at 60 to the sides 34 of the pan, and these pins pass through suitable openings in the ends of two opposite arms 61 55

of the spider frame (see Figure 2). The other two arms 62 are left free as shown in Figure 1.

A centering device can be used in combination with the clamp if desired, although the patch can be affixed without the centering device if necessary. This centering device includes the member 25 which has the beveled shoulders 26, which shoulders are adapted to co-act with the beveled shoulders 27 of the patch 28. The reason for this is that under pressure the beveled perimeters will co-act to firmly seal the beveled perimeter of the patch. The patch is received within the sleeve 29 which is slidably engaged with the portion 25, and which is spring urged by means of the spring 30. The small flange 31, which is an integral part of the portion 25, serves to retain the spring between the ring 29 and the portion 25. The centering device is a complete unit in itself, and can be used as such.

The pan 24 can be built in an approximately rectangular shape as shown by the character 63 in Figure 2 in order to accommodate a longer and narrower patch when desired. In this case when the centering device is used, it can be also made in an elongated shape.

A steel disc 64 having a cup shape cavity 65 is attached by means of a short chain 66 to the frame of the device. The base of the device is represented by the character 37.

When it is desired to attach a cold patch to the tube, the telescoping member 20 is pulled outwardly, thereby creating a long lever arm, and the patch is inserted in the sleeve 29, and the lever is pulled in the normal direction as indicated by the arrow 38.

Before exerting the extremely large pressure necessary for affixing the cold patch, however, the disc 64 must be inserted in the pan 24 so that the pressure can be transmitted directly to the patch through the solid posts 12 and 22 and through the member 53. Before the disc 64 is inserted, the plunger 41 will be in the raised position, and the arms 61 of the spider frame will be directly under the heads of the pins 58. The heads of these pins are high enough above the pan rim to allow insertion of the disc 64 through the space 67. This is illustrated more clearly in Figure 1, and by the dotted lines in Figure 6.

When the maximum pressure is now brought downwardly the disc 64 will absorb all of the strain so that the same can be transmitted directly through solid metal surfaces to the patch without having the tendency of breaking any of the parts. Furthermore, the engagement of the rounded surface 54 of the member 53 with the rounded cavity 65 permits of a pivoting arrangement on the disc 64, which pivot is at a low point, thus attaining the maximum effect of securing a positive pressure on all points of the area of the patch, even in spite of variations in the thickness of the tube under the patch. The pressure will be transmitted efficiently against the entire area of the patch without placing any undue strain upon any other parts of the machine.

When a hot patch is desired, the disc 64 is not used, and the device functions as shown in Figures 3 and 4. In this case, gasoline can be burned in the pan, or else a solid disc of fuel such as 35. It will be noted that in using this type of patch that the four arms of the spider bear against the shoulder 57 and the rim of the pan 24. This provides means for attaining an efficient pressure on the outer circumference or perimeter of the patch, and provides

a suitable swivelling effect on the spider frame against the shoulder 57 so that in this case also the pressure will be transmitted efficiently at the desired angle against the patch, and yet permitting fuel to be inserted in the pan.

If a solid fuel is used, it can also be placed in the opening 67 similarly to the process used in placing the steel disc 64 therein.

It will be noted from Figure 6 that when the cold patch is applied and the disc 64 is used that the spider 55 is free, and does not function in the apparatus except to center the same, since the length of the post 22 is made long enough so that as the member 53 bears against the disc 64 there will be no pressure exerted against the arms 61 and 62.

This entire arrangement permits the use of the entire device as a complete unit without the necessity of using any separate parts, and also provides the necessary functions of efficient pressures transmitted at the proper angles with pivoting points being arranged at the lowest possible points.

A preferred form of my invention is illustrated in Figures 4 and 5. In this form, the lever 39 (see Figure 2) is made of a suitable bar of a constant length which does not require the extra machining for the telescoping lever.

The plunger 40 includes the plunger head 41 having the arcuate portion 42 which is adapted to co-act with the cam member 17. The plunger head 41 rides within the opening 43 which receives the spring 44, which spring tends to raise the plunger similar to the spring 15 in the other modification. The plunger 40 includes the recess 45, which recess receives the spring 46.

Bearing against the spring 46 is the further plunger 47 through which is passed the pin 48. The pin 48 is made of a high grade steel having great shearing strength. It will be noted from Figure 5 that the pin passes through both sides of the plunger. The pin is guided by means of the vertical slots 52 which terminate in the lateral slot 49.

The lateral slot 49 passes practically 90 degrees about the periphery of the plunger 40 and is slightly enlarged into the opening 50 at the extremities thereof.

It will be noted from Figure 5 that there are two vertical slots 52 with two lateral slots 49, with the lateral slots arranged oppositely. The balance of the structure beneath the plunger 47 is the same as the modification shown in Figure 3. The junction between the slots include the cutaway portion 51 to insure a positive movement of the pin 48 vertically so there will be no binding or jamming of the same.

The spring 48 is made of sufficient tension to have a pressure range approximately between forty to sixty pounds or thereabout.

The operation of this modification will now be explained: In case it is desired to affix a patch to the tube 36 using the hot patch, the pan 24 is filled with the fuel and ignited after the patch 28 is inserted within its proper position in the sleeve 29. The pin 48 is positioned to ride vertically in the vertical slots 52 during the process of applying the hot patch. During the burning of the fuel, the lever 39 is pulled over as described and the cam 17 forces the plunger head 41 and the plunger 40 downwardly.

However, since the spring 46 will only develop a certain maximum pressure of not over sixty pounds or so approximately, the effective pressure against the patch can not be over this amount.

by virtue of the pin 48 which is now moving freely within the vertical slots 52. As a result, the patch will be applied without any excess in pressure.

- 5 To apply the cold patch, the plunger 41 is turned approximately ninety degrees allowing the pin 48 to pass through the lateral slots 49 and into the openings 50. When the lever 39 is pulled over, the maximum pressure will pass independently of the spring 46 through the outer periphery of the plunger 40, thence through the pin 48 to the plunger 47, and in this way, the total maximum pressure due to the leverage will be exerted against the patch, which, of course, in this case does not require the fuel means.

In this way a cold patch can be applied readily by merely turning the plunger 47 in the manner described, which provides a simple and convenient method of achieving this result, and since the pin 48 is made sufficiently large and is of a high grade of steel, it will easily absorb the maximum pressure without resulting in breakage of any of the parts.

It will be understood, of course, that the entire lower part of the device, such as the pan, the steel disc 64, the loosely engaged spider frame, and the like can be used also with this latter form, if desired, so that any interchangeable combination can be made.

20 It will now be seen that I have provided an apparatus for applying either hot or cold patches as described with a simple arrangement for selectively controlling either method in a unit apparatus.

25 It will be seen further that I have provided means for accomplishing this result to accommodate different forms or sizes of patches, that I have devised a machine for effectively sealing a patch either with heat or without heat with the pressures being applied under suitable pivoting arrangements to insure a maximum efficient pressure against the patch without the danger of breaking any of the parts of the machine, and that I have provided all of these means in a structure of sufficient simplicity to insure a reasonable cost of manufacture.

30 Some changes may be made in the construction and arrangement of the parts of my invention without departing from the real spirit and purpose of my invention, and it is my intention to cover by my claims any modified forms of structure or use of mechanical equivalents, which may be reasonably included within their scope.

I claim as my invention:

35 1. A tube patching apparatus comprising a plunger, a lever for forcing the plunger downwardly, a further plunger adapted to be resiliently forced against a tire patch by the first mentioned plunger, and means for locking the two plungers together independently of said resilient means to function as a continuous solid unit.

2. A tube patching apparatus comprising a plunger, a lever for forcing the plunger downwardly, said plunger having a recessed cavity, a spring within the cavity, and said plunger having vertically positioned slots, lateral slots terminating the lower limits of the vertical slots, a lower plunger including a pin attached thereto received within the said recessed cavity so that said pin is received within said slots.

3. A tube patching apparatus comprising a plunger, a lever for forcing the plunger downwardly, said plunger having a recessed cavity, a spring within the cavity, and said plunger having vertically positioned slots, lateral slots ter-

minating the lower limits of the vertical slots, a lower plunger including a pin attached thereto received within the said recessed cavity so that said pin is received within said slots, said lateral slots being arranged oppositely to cause engagement of the pin at the extremities thereof to cause transference of pressure to the said lower plunger when the plunger is turned to cause such engagement. 5

4. A tube patching apparatus comprising a plunger, a lever for forcing the plunger downwardly, said plunger having a recessed cavity, a spring within the cavity, and said plunger having vertically positioned slots, lateral slots terminating the lower limits of the vertical slots, a lower plunger including a pin attached thereto received within the said recessed cavity so that said pin is received within said slots, said lateral slots being arranged oppositely to cause engagement of the pin at the extremities thereof to cause transference of pressure to the said lower plunger when the plunger is turned to cause such engagement, a fuel receiving heating pan attached to the lower plunger. 10 15 20

5. A tube patching apparatus comprising an upper plunger, a lever for forcing said plunger downwardly, a lower spring urged plunger received within the said plunger, means for causing selective resilient or positive pressures against the lower plunger including a pin attached to the lower plunger, said upper plunger having vertical slots including lateral extensions adapted to receive the pin so that the pin rides vertically in the said vertical slots when a lesser pressure is desired, and locks both plungers to 30 permit transference of a greater direct pressure through the said plungers. 35

6. A tube patching apparatus comprising an upper plunger, a lever for forcing said plunger downwardly, a lower spring urged plunger received within the said plunger, means for causing selective resilient or positive pressures against the lower plunger including a pin attached to the lower plunger, said upper plunger having vertical slots including lateral extensions adapted to receive the pin so that the pin rides vertically in the said vertical slots when a lesser pressure is desired, and locks both plungers to permit transference of a greater direct pressure through the said plungers, varied sized patch holding means including fuel receiving means adapted to permit sealing of varied sized patches to a tube attached to the lower plunger. 40 45 50

7. A tube patching apparatus comprising a plunger, pressure means for forcing the plunger against a patch, means for supplying heat to the patch, including a fuel pan attached to the plunger, said plunger including a reduced diameter extension, a cross-arm member loosely engaged therewith adapted to be forced against the edges of the fuel pan, said fuel pan including headed pins attached thereto received through openings in the said ends of the cross-arms. 55 60 65

8. A tube patching apparatus comprising a plunger, pressure means for forcing the plunger against a patch, means for supplying heat to the patch, including a fuel pan attached to the plunger, said plunger including a reduced diameter extension, a cross-arm member loosely engaged therewith adapted to be forced against the edges of the fuel pan, said fuel pan including headed pins attached thereto received through openings in the said ends of the cross-arms, said reduced diameter extension including an arcuate member attached at the end thereof, 70 75

a pressure receiving disc arranged to be inserted in the pan against which the arcuate member bears when a patch is being applied under great pressure.

9. A tube patching apparatus comprising a plunger, means for applying pressure against the plunger, said plunger having a recessed cavity, a spring within the cavity, and said plunger having vertically positioned slots, lateral slots terminating the lower limits of the vertical slots, a lower plunger including a pin attached thereto received within the said recessed cavity so that said pin is received within said slots, said lateral slots being arranged oppositely to cause engagement of the pin at the extremities thereof to cause transference of pressure to the said lower

plunger when the plunger is turned to cause such engagement, a fuel receiving heating pan attached to the lower plunger, said lower plunger including a reduced diameter extension, a cross-arm member loosely engaged therewith adapted to be forced against the edges of the fuel pan, said fuel pan including headed pins attached thereto received through openings in the said ends of the cross-arms, said reduced diameter extension including an arcuate member attached at the end thereof, a pressure receiving disc arranged to be inserted in the pan, said disc having an arcuate cavity against which the said arcuate member bears when a patch is being applied under great pressure.

CLARENCE E. DUNLAP. 15
